UNITED STATES PATENT OFFICE.

JOHN F. McCANNA, OF CHICAGO, ILLINOIS.

LIQUID-CIRCULATING APPARATUS FOR ENGINES.

No. 802,404.

Specification of Letters Patent.

Patented Oct. 24, 1905.

Application filed December 29, 1904. Serial No. 238,764.

To all whom it may concern:

Be it known that I, JOHN F. McCANNA, a citizen of the United States, residing at Chicago, in the county of Cook and State of Illinois, have invented certain new and useful Improvements in Liquid-Circulating Apparatus for Engines, of which the following is a specification, reference being had therein to the accompanying drawings.

My invention is in the nature of a pump designed to be operated by fluid-pressure, and I have shown it as operated by pressure from the cylinder of an explosion-engine and serving to circulate water from the cooling-tank through the water-jacket of the cylinder and incidentally to serve as an indicator of its operation and a means of readily ascertaining the temperature of the circulating fluid.

To illustrate my invention, I annex hereto a sheet of drawings, in which the same reference characters are used to designate identical parts in all the figures, of which—

Figure 1 is a sectional view through the front end of an automobile, showing my invention applied thereto. Fig. 2 is a sectional view through the check-valves, and Fig. 3 is a sectional view through the operating apparatus.

The jacket *a* of the cylinder is connected by the pipes *b* and *c* with the cooling-tank *d* in the customary manner. In the lower pipe *c* I place a pair of check-valves *e* and *f* on either side of a short pipe *g*, leading to the operating apparatus, which I will designate as a whole by the character *h* and which is connected to the explosion end of the cylinder by the pipe *i*, which contains the cock *j*, by which the apparatus can be shut off when desired. The valve-casing and pipe connection is conveniently formed by a section *k*, having the valve-seats *l* and *m*, with which the ball-valves operate in the customary manner. The body of the apparatus *h* is a cylindrical shell having one or more sides partially open, as shown, to expose the glass tube *n*, having a fluid-tight seat therein. The upper end is closed by a head *o*, having the tubular extension *p*, whose upper end is connected to the pipe *i* in any desired manner. The head *o* is secured in place and the glass tightly clamped between the packing-rings to make fluid-tight joints by the nut *q* coöoperating with the threaded upper end of the body *h* and engaging the upper edge of the head. A float *r*, whose cross-section substantially fills the

tube *n*, has the rod *s* extending upward and carrying the oppositely-faced valves *t* and *u*, adapted to coöperate with the valve-seats *v* and *w*, formed in the head *o* and constituting 60 the ends of the small passage *x*, through which the upper end of the rod *s* passes.

The operation of the apparatus is as follows: The apparatus may be assumed to be in the position shown in Fig. 3, with the cylinder-piston starting up to compress the charge preparatory to ignition. As the pressure becomes sufficient the water standing in the tube *n* is forced down, and the float *r* goes with it until the valve *u* rests upon the seat 65 *w*, when of course the pressure on the water ceases, and that is before the high pressure in the cylinder can cause a greater movement of the water than is desired. Of course, as the water descends under the pressure prior to 70 75 the closing of the valve *u* the valve *f* is held closed and valve *e* is raised, so the water is forced into the jacket *a*. When the pressure in the cylinder is released to less than that of the head of water in the tank, the float is 80 raised until the valve *t* engages the seat *v*, thus limiting the amount of water that can pass through the raised valve *f*. By thus drawing the water into the apparatus from the cooling-tank and forcing it out into the 85 water-jacket the desired circulation is obtained. Incidentally the movement of the float *r*, which is of course visible, inasmuch as the apparatus *h* is on the dashboard *y*, serves as an indication of the operation of the 90 engine, and by feeling the glass *n* the heat of the circulating water can be readily and instantly ascertained, two features of value to the user.

While I have shown and described my invention as applied to an explosion-engine for circulating cooling-water through the jacket, it will be readily seen that it is capable of other uses, and also that while I have shown it as embodied in the form which I at present consider best adapted to carry out its purposes it is capable of modifications, and that consequently in the interpretation of the following claims I do not desire to be limited except as may be necessitated by the prior art. 95 100 105

What I claim as new, and desire to secure by Letters Patent of the United States, is—

1. In a device of the class described, the combination with the chamber adapted to be connected with a source of intermittent fluid-pressure, of a liquid-supply also connected therewith, check-valves for said liquid, and 110

means for applying the pressure to the liquid in the chamber up to a certain degree and then shutting it off from said chamber while it remains above said degree.

5 2. In a device of the class described, the combination with the source of intermittent fluid-pressure, of the liquid - reservoir, pumping mechanism operated by the fluid-pressure co-operating with said liquid - reservoir, and
10 means for operating said pumping mechanism under a certain pressure and shutting it off when it rises above said certain pressure.

3. In a device of the class described, the combination with the source of intermittent fluid-pressure, of the liquid - reservoir, pumping mechanism operated by the fluid-pressure co-operating with said liquid - reservoir, and means for operating said pumping mechanism under a certain pressure and shutting it off
15 20 when it rises above said certain pressure, said means consisting of a passage between the pumping mechanism and the source of intermittent fluid-pressure having valve-seats at its ends, a float in the liquid-reservoir having an extension through said passage and provided with valves to coöperate with said seats, all combined and coöperating substantially as and for the purpose described.

4. In a device of the class described, the combination with a chamber adapted to be connected with a source of intermittent fluid-pressure, of connections therewith to a liquid-supply, check - valves in said connection for the purpose described, a passage in said chamber for the fluid under pressure, valve-seats at the ends of said passage, and a float in said chamber having an extension through said
30 35

passage and provided with valves to coöperate with said seats; all combined and coöperating substantially as and for the purpose described.

5. In a device of the class described, the combination with the transparent chamber adapted to be connected with a source of intermittent fluid - pressure, of a liquid-supply also connected therewith, check - valves for said liquid, a float in said chamber, and means for applying the pressure to the float and liquid in the chamber up to a certain degree and then shutting it off therefrom while it remains above said degree.

6. In a device of the class described, the combination with the gas-engine, of the water-jacket surrounding the cylinder, the cooling-tank, double connections between the water-jacket and the cooling-tank, a chamber connected with the engine-cylinder, a pair of check-valves in one of the connections between the cooling-tank and the water-jacket, a pipe connecting the chamber with the last-mentioned connection between the check-valves, a passage in said chamber, valve-seats at its ends, and a float in said chamber having an extension through said passage and provided with valves to coöperate with said seats; all combined and coöperating substantially as and for the purpose described.

In testimony whereof I affix my signature in presence of two witnesses.

JOHN F. McCANNA.
